UNITED STATES PATENT OFFICE.

CHRISTIAN G. SINGLEY, OF MANHEIM, PENNSYLVANIA.

METHOD OF PACKING CIGARS.

No. 908,809.

Specification of Letters Patent.

Patented Jan. 5, 1909.

Application filed November 20, 1908. Serial No. 463,519.

To all whom it may concern:

Be it known that I, CHRISTIAN G. SINGLEY, a citizen of the United States, residing at Manheim, in the county of Lancaster and State of Pennsylvania, have invented certain new and useful Improvements in Methods of Packing Cigars, of which the following is a specification, reference being had therein to the accompanying drawing.

10 My invention relates to a new and improved method of putting up cigars, in the form of tri-twists arranged in bunches, dispensing with the former mode of tying the bunches at each end, to produce and retain 15 the desired shape, thus saving time and labor in preparing and packing said bunches.

The purposes of the invention are attained by the mechanism, devices and means illustrated in the accompanying drawings, 20 with similar reference characters to designate like parts throughout the several views in which:—

Figure 1, is a plan view of a case or box filled or packed with the desired number 25 of such twisted cigars, being preferably arranged in bunches of three. Fig. 2, is a left end elevation of the same box, with bunches of twisted cigars therein, the box and lid appearing in section. Fig. 3, is a detached 30 view of a bunch before pressing. Fig. 4, is a view showing the head ends of the detached bunch in elevation. Fig. 5, is a view showing the butt ends of the same bunch.

In the drawing, 1, designates the usual 35 cigar box of the required length, width and depth, made of any approved material and adapted to have packed therein, tri-twist bunches of cigars, the bunches being designated by 2, and the cigars by 3, arranged 40 in layers of sixteen cigars to a layer, except-

ing the end bunches of each layer which have only two such cigars, so that when the box is filled there will be packed therein fifty of said cigars. In Fig. 1, is shown the upper layer of sixteen cigars. It will here 45 be understood that the number of such cigars put up in boxes is not limited to fifty for the boxes may be increased or diminished in size according to the number of such cigars desired to be packed therein. 50

It will here be remarked that twisted cigars similar to those hereinbefore referred to have heretofore been made and twisted together as shown in Fig. 3. In this case the bunches of such cigars have always been 55 tied by strings at each end to preserve the desired shape, but by the present method which consists of interlacing the cigars while damp or green and subjecting them to pressure, such tying of the ends is dispensed 60 with as superfluous, as the cigars by this method of packing them in boxes is sufficient to preserve them in the desired form.

Having thus described the cigars in question and the method of putting them up 65 what is considered new and desired to be secured by Letters Patent is:—

The method of packing cigars in boxes, consisting of interlacing three or more cigars into a bunch, and compressing said 70 bunch while damp, for the purpose of retaining the cigars in said bunches without the use of any other tying means.

In testimony whereof I affix my signature in presence of two witnesses.

CHRISTIAN G. SINGLEY.
